COMBINATION COOLING CRADLE AND DRIP TRAY FOR KEG TYPE CONTAINERS

James B. Kelley, Jr., 4019 Healey Court, St. Louis, Mo.

Filed Aug. 2, 1965, Ser. No. 86,396

Term of patent 14 years

(Cl. D67—3)

FIG. 1

FIG. 2

FIG. 3

FIG. 1 is a perspective view of a combination cooling cradle and drip tray for keg type containers as seen from above showing my new design;

FIG. 2 is a side elevational view showing my design, the opposite side not shown being substantially the same; and

FIG. 3 is an elevational view of the end opposite the drip tray end shown in FIG. 1.

The dominant features of my design reside in those portions shown in full lines.

I claim:

The ornamental design for a combination cooling cradle and drip tray for keg type containers, substantially as shown and described.
